Primary Examiner — Melanie H Tung*Assistant Examiner* — Darmawan Truong(74) *Attorney, Agent, or Firm* — McGinn I.P. Law Group, PLLC(57) **CLAIM**

The ornamental design for display screen with an animated icon for a start switch, as shown and described.

DESCRIPTION

FIG. 1 is a front view of a display screen with an animated icon for a start switch showing our new design; and, FIG. 2 is a second image thereof.

The appearance of the transitional image sequentially transitions between the images shown in FIGS. 1-2. The process or period in which one image transitions to another forms no part of the claimed design.
